UNITED STATES PATENT OFFICE.

EDMUND GALE JEWETT, OF BELLINGHAM, WASHINGTON.

APPARATUS FOR DISTILLING WOOD.

No. 824,372.

Specification of Letters Patent.

Patented July 3, 1906.

Application filed June 29, 1905. Serial No. 267,628.

To all whom it may concern:

Be it known that I, EDMUND GALE JEWETT, a citizen of the United States, residing at Bellingham, in the county of Whatcom and State of Washington, have invented certain new and useful Improvements in Apparatus for Distilling Wood; and I do declare the following to be a full, clear, and exact description of the invention, such as will enable others skilled in the art to which it appertains to make and use the same.

My invention is an improved apparatus for distilling wood for the purpose of obtaining alcohol, tar, turpentine, and other products therefrom; and it consists in the construction, combination, and arrangement of devices hereinafter described and claimed.

In the accompanying drawings, Figure 1 is a vertical sectional view of a wood-distilling apparatus embodying my improvements, and Fig. 2 is a horizontal sectional view of the same.

The furnace 1 is here shown as of circular form and is provided with a relatively narrow grate 2, which extends diametrically across the same, and with a pair of shorter grates 3 at opposite sides of the furnace and arranged at right angles to the grate 2. Under each grate is an ash-pit, and in each ash-pit is located an air-pipe 4, to which air under a suitable degree of compression is supplied, and each of said air-pipes is provided with upwardly-extending air-discharging nozzles 5, which are opposite the spaces between certain of the bars of the grates and are disposed in mixing-pipes 6, to which gas is supplied by gas-pipes 7. The air from the pipes 4 commingles with the gas in the mixing tubes or pipes and serves to greatly promote the combustion of the gas, as will be readily understood. Within the furnace are retorts 8, which may be of any suitable number. Four of the retorts are here shown in the furnace disposed in two groups on opposite sides of the grate 2, the said groups of retorts being spaced and separated by the said grate 2. The shorter grates 3 partially enter the spaces between the retorts of the several groups. Each of the said retorts has its lower portion disposed in a shield 9, with which the furnace is provided. Said shields are here shown as constructed of fire-brick. Each of the said shields forms a chamber 10 for the reception of the lower end of one of the retorts, and each of said retorts has a funnel-shaped bottom 11, from which leads a conduit 12 for the products of distillation. The upper portion of each of the retorts is here shown as protected from the flames in the furnace by a metallic shield 13, which rests on the fire-brick shield 9. A stopper 15, Fig. 2, which is made of asbestos, is between each of the retorts and the fire-brick shield 9, as shown. Each of the retorts is made of metal and is here shown as cylindrical in form. The upper end of each retort passes through an opening in the top of the furnace and is provided with a cover 17, which is here shown as of substantially conical form. The diameter of the covers 17 is greater than that of the retort, so that the outer edges of the covers project beyond the outer sides of the retorts and lie in trenches 18, with which the top of the furnace is provided. Clay or other suitable plastic material or a readily-fusible metal is placed in the said trenches and serves to effectually seal the covers of the furnace to prevent the escape of the products of distillation therefrom, as will be readily understood. From the top or cover of each retort is suspended a crate 19, which extends nearly to the bottom of the retort. The said crate comprises outer and inner vertical bars 20 21, radially-disposed bars 22, which connect said outer and inner bars, hoop-bars 23, secured to the inner sides of the vertical bars 20, and the smaller hoop-bars 24, surrounding and secured to the outer sides of the vertical bars 21. These hoop-bars serve as braces for the crates, and are moved with the crates when they are lifted out for recharging. The radial bars 22 are inclined and disposed in downwardly-converging planes and serve to support annular bars 26, which divide the crate into vertical sections and which serve to support the wood that is placed upright in the said sections and is introduced into the said sections by being passed through the spaces between the outer bars 20. By having the circular hoop-bars 24 detachable from the bars 21, so that they may be raised or lowered, the placing of the wood in the sections of the crate is greatly facilitated, as will be understood. The inner vertical bars 21 of the crates form a central vertical shaft 27. Under the bottom of each section of the crate is a funnel-shaped metallic bottom 28, having a central opening through which the shaft 27 extends and which serves to convey the products of distillation from the several sec-

tions of the crate to the said shaft, so that the products of distillation are caused to drop into the said shaft 27 and are hence conveyed to the conduit 12. The metal bottoms are secured in any suitable manner to the radial bars 22 and are removable with the retorts 8. In the shaft 27 of each of the crates is a water-pipe 29, which is secured to and supported by the top 17 and is provided with a plurality of 10 radially-disposed inclined discharge-pipes 30, the latter being disposed in the upper end of the respective sections of the crate and the function of which is to enable water to be discharged into the crates for the purpose of 15 spraying the contents thereof. Also in each of the retort-tops 17 is a pipe 31 for the reception of a thermometer. The pipes 33 serve as spray-pipes for the upper retorts.

It will be understood that when the top of 20 one of the retorts is raised or lowered the crate which is secured thereto and depends therefrom will be also raised and lowered, and in practice I employ suitable cranes or other devices for raising and lowering the tops and 25 the crates, so that the crates may be removed from the retorts for the purpose of charging them and of removing the charcoal therefrom. Hence the charging of the retorts is very greatly facilitated.

30 From the foregoing description, taken in connection with the accompanying drawings, the construction and operation of the inven-

tion will be readily understood without requiring further explanation.

Various changes in the form, proportion, 35 and the minor details of construction may be resorted to without departing from the principle or sacrificing any of the advantages of the invention.

Having thus described my invention, what 40 I claim as new, and desire to secure by Letters Patent, is—

1. In a wood-distilling apparatus, a series of retorts, a furnace extending between the retorts, crates in the retorts, said crates 45 comprising radial bars, annular bars secured to said radial bars, a water-pipe and laterally-extending spray-pipes, substantially as described.

2. In a wood-distilling apparatus, a retort, 50 a furnace therein, a series of crates in the retort, said crates each comprising a series of inclined radial bars, a series of annular bars supported upon the radial bars, funnel-shaped metal bottoms, a water-pipe, and 55 spray-pipes connected thereto, substantially as described.

In testimony whereof I have hereunto set my hand in presence of two subscribing witnesses.

EDMUND GALE JEWETT.
